Primary Examiner—Doris V. Coles*Assistant Examiner*—Elizabeth A. Albert(74) *Attorney, Agent, or Firm*—Foley & Lardner(57) **CLAIM**

We claim the ornamental design for a food pan, as shown and described.

DESCRIPTION

FIG. 1 is a top perspective view of a food pan illustrating my design;

FIG. 2 is a top plan view thereof;

FIG. 3 is a rear side elevational view thereof;

FIG. 4 is a bottom plan view thereof; and,

FIG. 5 is a sectional view thereof taken along line 5—5 of FIG. 2.

The ornamental design which is claimed is shown in solid lines in the drawings. The broken lines in the drawings are for illustrative purposes only and form no part of the claimed design.
